CLAIM

The ornamental design for a pet toy, as shown and described.

DESCRIPTION

FIG. 1 is a top right perspective view of a pet toy embodying my design;
 FIG. 2 is a top left perspective view of the pet toy of FIG. 1;

FIG. 3 is a front elevational view of the pet toy of FIG. 1;

FIG. 4 is a rear elevational view of the pet toy of FIG. 1;

FIG. 5 is a left end view of the pet toy of FIG. 1;

FIG. 6 is a right end view of the pet toy of FIG. 1;

FIG. 7 is a top plan view of the pet toy of FIG. 1; and,

FIG. 8 is a bottom plan view of the pet toy of FIG. 1.

1 Claim, 4 Drawing Sheets
